UNITED STATES PATENT OFFICE.

BERTRAND P. KENYON, OF GRAND RAPIDS, MICHIGAN, ASSIGNOR TO THE MICHIGAN VAPOR STOVE COMPANY, OF SAME PLACE.

DESIGN FOR A CASTER-PINTLE.

SPECIFICATION forming part of Design No. 31,793, dated November 7, 1899.

Application filed October 11, 1899. Serial No. 733,323. Term of patent 14 years.

To all whom it may concern.

Be it known that I, BERTRAND P. KENYON, a citizen of the United States, residing at Grand Rapids, in the county of Kent and State of Michigan, have invented and produced a new and original Design for Caster-Pintles, of which the following is a specification, reference being had to the accompanying drawings, forming a part thereof.

10 Figure 1 is a side elevation of a caster-pintle, showing my new design; and Fig. 2, an end view of the same.

As shown in the drawings, the leading or material feature of my design consists in the 15 circumferential enlargements C D E, arranged substantially equidistant upon the body of the pintle, the enlargement E being tapered toward the middle enlargement D.

A is a cylindrical body; B, a flange sur-

rounding the same at a short distance from 20 the lower end thereof; C, a circumferential enlargement at the upper end of the body; E, another circumferential enlargement adjacent to the flange B and tapering upward, and D a third circumferential enlargement 25 located midway between the enlargements C and E.

Having described my invention, what I claim, and desire to secure by Letters Patent, is—

The design for a caster-pintle as herein shown and described.

In testimony whereof I affix my signature in presence of two witnesses.

BERTRAND P. KENYON.
